UNITED STATES PATENT OFFICE.

WILLIAM H. DODGE, OF MANHATTAN, KANSAS.

STREET-CLEANING MACHINE.

1,090,034.

Specification of Letters Patent. Patented Mar. 10, 1914.

Application filed August 11, 1913. Serial No. 784,141.

To all whom it may concern:

Be it known that I, WILLIAM H. Dodge, citizen of the United States, residing at Manhattan, in the county of Riley and State of Kansas, have invented new and useful Improvements in Street-Cleaning Machines, of which the following is a specification.

My present invention pertains to machines for cleaning asphalt and other hard and smooth roadways.

The general object of the invention is the provision of a machine of the character stated that is simple and inexpensive in construction, efficient in operation, and is adapted to be expeditiously and easily adjusted to take up wear as well as to enable the machine to operate to advantage under different conditions.

The invention in all of its details will be fully understood from the following description and claims when the same are read in connection with the drawings, accompanying and forming part of this specification, in which:

Figure 1 is a side elevation of the machine constituting the best practical embodiment of my invention that I have as yet devised. Fig. 2 is a longitudinal vertical section of the machine. Fig. 3 is a horizontal section of the machine, taken in a plane above the ground wheels from which I prefer to take motion to drive the elevator. Fig. 4 is a detail plan of a modified gatherer hereinafter specifically referred to.

Referring by numeral to the said drawings and more particularly to Figs. 1 to 3 thereof: 1 is the body of my novel machine which may be of any configuration compatible with the function of the machine without affecting my invention. The said body is provided at 2 with a receptacle for dirt and other substance taken up from a roadway, and the receptacle is provided at 3, Figs. 1 and 3, with a hinged door to facilitate removal of the collected dirt and other substance therefrom. The door 3 may obviously be normally secured in closed position by any conventional means. Fixed in the body 1 and extending downwardly and forwardly from the upper portion of the forward wall of the receptacle 2 is an inclined wall 4 which terminates at its forward end in a forwardly directed portion 5 that extends to a point closely adjacent the roadway or surface on which the machine is operated.

As will be observed by reference to Fig. 2 the body is provided with side walls 6 that extend upwardly from the inclined wall 4 with a view to preventing the lateral escape of dirt and other substance incidental to the raising thereof, as hereinafter described. Journaled in suitable bearings in the lower portion of the body 1 is a transverse shaft 7, and fixed on the said shaft are ground wheels 8. Also fixed on the shaft 7 is a sprocket gear 9. Suitably mounted in the body above the inclined wall 4 and between the side walls 6 are drums 9 and 10, and passed around or arranged on the said drums is an endless apron 11 having at intervals of its length blades 12. The said blades serve to move before them dirt and other substance from the platform or wall portions 5 upwardly on the inclined walls 4 and deposit the said dirt and other substance in the receptacle 2. The said function is performed by the blades 12 on the upward and rearward traverse of the same. The endless apron 11 is driven from one of the ground wheels 8 through the medium of a driving connection which preferably comprises a sprocket gear 13 fixed with respect to the drum 10 and a sprocket belt 14 mounted on and connecting the gears 9 and 13, as clearly shown in Fig. 1. At this point I would have it understood that the illustrated embodiment of my invention is designed to be pushed by a laborer or drawn by draft animals, and that in said embodiment I prefer as described to drive the endless apron 11 from one of the ground wheels 8. I would also have it understood that when my invention is incorporated in a motor driven machine, as well as in a horse-drawn machine, the endless apron 11 may be driven by a motor carried by the machine without involving departure from the scope of my claimed invention.

By reference to Fig. 3 it will be observed that the transverse shaft 7 is provided with two cranks 15 and a third crank 16, the latter being arranged intermediate of the cranks 15. Connected to and extending forwardly from the cranks 15 are rods 17, and carried at the forward ends of the said rods and between the said ends is a scraper 18 arranged transversely of the machine at the forward end thereof. The said scraper 18, as its name imports, is designed to scrape or rake dirt and other substance from the roadway over which the machine is moved and assure the placing of

such dirt or other substance on the platform 5. The rake 18 is reciprocated forwardly and rearwardly by the crank connection shown when the machine is moved forwardly, and in order to depress the rake during its rearward traverse and raise the rake incidental to its forward traverse I provide the mechanism shown in Figs. 2 and 3. In addition to the intermediate crank 16 of the shaft 7 the said mechanism comprises a vertically-rocking lever, journaled in the body at the points 21 and having a rear arm 22 arranged under the intermediate crank 16 and also having forward 15 side arms 23 that terminate at their forward ends in eyes 24 in which the rods 17 are loosely arranged as shown. It will be manifest that during the forward stroke of the rods 17 and the rake 18, the crank 16 will depress 20 the rear lever arm 22, and in that way raise and maintain in raised position the forward arms 23 of the lever and the rods 17 and rake 18. On the rearward traverse of the rake, however, the crank 16 will be out of 25 engagement with the lever arm 22, and this will enable the rake 18 and its appurtenances to gravitate so that the rearward traverse of the rake will take place while the rake bears on the roadway. This manner of operating the rake will be appreciated as materially advantageous when it is stated that the raising of the rake subsequently to the placing of dirt by the same on the platform 5, leaves all of the dirt on said platform in 30 readiness for the same to be elevated by the blades 12 of the apron 11. Fixed with respect to the body and disposed immediately under the platform 5 is a blade 30 which has for its function to lift from the roadway dirt or other substance that may have 35 become caked on the roadway. In order to properly position the blade 30 relative to the surface of a roadway and to take up or compensate for wear of the said blade, I 40 mount the rear portion of the body 1 on a shaft 32 that is journaled in bearings carried by the body and is provided at its ends with crank arms 33 on which are mounted 45 loosely wheels 34. Any suitable means may 50 be employed to rock the shaft 32 about its axis and raise or depress the rear portion of the body 1 that is fulcrumed or centered on the shaft 7. I prefer, however, to employ for 55 the purpose a beveled gear 35, fixed on the shaft 32, and a beveled gear 36 that is intermeshed with the gear 35 and is fixed on a shaft 37, extended forwardly to a point 60 in front of the body 1 and there provided with a hand wheel 38. It will be manifest 65 that by turning the said hand wheel 38 the machine operator is enabled to raise or lower the forward portion of the body 1 and the blade 30 as occasion demands. Pivoted at the points 40 to the body 1 are wings or 70 gatherers 41. These gatherers are designed

to extend forwardly and laterally from the body and to bear on the ground or roadway with a view to enabling the machine to remove dirt and other substance from a path wider than the platform 5 of the machine. It will be manifest that the gatherers 41 can be extended outwardly to a greater or less extent so that the machine can be used in wide and narrow passages; and it will also be manifest that when it is desired to move the machine flush against the side of a curb the gatherer 41 adjacent the curb may be made to extend forwardly parallel to the side walls 6 of the body. The gatherers 41 may be adjusted and adjustably fixed by any suitable means without involving departure from my claimed invention. I prefer, however, to provide the gatherers with handles 42 possessed of resiliency, and to fix curvilinear racks 43 to the body 1 in such positions that the handles 42 can be sprung into and out of seats in the racks. 75

In lieu of the blade-like gatherers shown in Figs. 1 to 3 rotatable brushes may be used as gatherers. One of the said brushes is shown in Fig. 4 and numbered 41^a, and by reference to the said figure, it will be seen that the shaft of the brush is connected through a universal joint 50 to a shaft 51 which in turn may be connected with the shaft 7 to derive rotary motion from the latter. It will also be seen by reference to Fig. 4 that a lever 42^a similar to the levers 42 is connected through an arm 52 with the shaft of the rotary brush, so that when the lever is swung the brush will be swung about the center of movement 53. Two of the rotary brushes and their appurtenances will of course be employed, and it is to be understood that racks such as the racks 43 or any other suitable means may be employed to adjustably fix the levers 42^a and the brushes 41^a in the positions in which they are placed. When the machine is to be drawn by horses or driven by a motor, it may be and preferably is provided at 60 with a seat for an operator. 100

I have entered into a detailed description of the construction and relative arrangement of the parts embraced in the present 115 and preferred embodiment of my invention, in order to impart a full, clear and exact understanding of the said embodiment. I do not desire, however, to be understood as confining myself to the said specific construction and relative arrangement of parts, as in the future practice of the invention such changes or modifications may be made as fairly fall within the scope of my appended claims. 120

Having described my invention, what I claim and desire to secure by Letters-Patent, is:

1. A street cleaning machine comprising a body having a platform, a transverse shaft 130

journaled in suitable bearings in the body and provided with ground wheels and also provided with cranks adjacent the ground wheels and a crank intermediate the first-named cranks, a transverse rake disposed in front of the body, rods interposed between and connected to the first-named cranks of the shaft and the rake, and a vertically-rocking lever fulcrumed in the body and having a rear arm positioned for coöperation with the intermediate crank of the shaft and also having forward arms terminating in eyes that loosely receive the said rods on the rake.

2. A street cleaning machine comprising a body having means to receive dirt and other substance removed from a street, a gravitating rake for transferring dirt and other substance from a street to the said means of the body, means for reciprocating the rake in the direction of the length of the machine, means for raising the rake preceding to the forward traverse thereof and for maintaining the rake in raised position during the said traverse, and means where-

by the rake is released and permitted to 25 gravitate at the completion of the forward traverse.

3. A street cleaning machine comprising a body having means to receive dirt and other substance removed from a street, a 30 drive shaft in the body, a transversely arranged rake movable forwardly and rearwardly, a driving connection intermediate the shaft and rake whereby the latter is reciprocated, and means actuated by the shaft 35 for maintaining the rake in raised position during its forward traverse and for releasing the rake and permitting it to gravitate to working position at the completion of said traverse.

In testimony whereof I have hereunto set my hand in presence of two subscribing witnesses.

WILLIAM H. DODGE.
